VIBRATING SHAMPOO DEVICE

Dan S. Berns and Carlos J. Cardona,
Los Angeles, Calif.

Application February 17, 1942, Serial No. 431,278

4 Claims.

(CL. 128—66)

This invention pertains to a vibrating shampoo device which is portable, self-contained and readily controllable, the device being adapted to shampoo or treat the hair and to massage the scalp, thereby facilitating the application of oils, stimulants and preparations useful in the treatment of scalp diseases, elimination of dandruff, etc.

Generally stated, the invention relates to a portable device having a body portion by means of which it can be readily held and manipulated. The body portion includes an electrically operated, vibratable element, such element being connected to a hollow shampoo head provided with suitable massage prongs, suction cups, bristles or the like. The device includes means whereby a supply of suitable liquids, such as oil or other preparation, is supplied to the shampoo head so that the preparation is effectively applied to the scalp during the shampooing or massaging operation.

It is an object of the present invention, therefore, to disclose a compact, relatively lightweight, portable vibrating shampoo device which includes a reservoir for whatever liquid preparation it is desired to use or apply.

A further object of the invention is to disclose and provide a vibrating shampoo device which positively ejects a desired liquid preparation into intimate contact with the scalp while the device is in use.

Other objects of the invention will become apparent to those skilled in the art from the following description of certain exemplary forms of the invention. In order to facilitate understanding of the invention, reference will be had to the appended drawing, in which:

Fig. 1 is a bottom view of the device embraced by this invention.

Fig. 2 is a longitudinal section taken generally along the plane II—II of Fig. 1.

Fig. 3 is a side elevation, partly broken away, of a modified form of device.

Fig. 4 is a section taken along the plane IV—IV of Fig. 3.

Fig. 5 is an enlarged fragmentary view of the shampoo head shown in Figs. 1 and 2, this figure being an axial section with the device at rest.

As shown in Figs. 1 and 2, the device may comprise a hollow body portion 10 preferably made of molded plastic or thin sheet metal and adapted to form a handle 11 by means of which the device may be readily grasped. Extending from the forward part of the body portion is a vibratable element 12 which may be in the form of a

relatively stiff magnetic metal bar adapted to be actuated by an electromagnet 13 suitably mounted within the body portion 10. Current to the electromagnet 13 may be supplied by flexible leads 14, a switch 15 being carried by the body portion adjacent the handle 11, such switch 15 being interposed in the leads 14 so as to permit the electromagnet 13 to be selectively operated.

10 The vibratable element 12 is preferably connected to the body portion or to the electromagnet 13, and a semicircular bend or curve 16 is formed in said member near its point of connection to the body or to the electromagnet. In Fig. 2 the point of connection between the vibratable element and the electromagnet 13 is indicated at 17. The curve or loop 16 reduces the strains which may be set up in the vibratable element 12 when it is rapidly vibrated under the influence of the electromagnet 13.

15 A hollow shampoo head is attached to the vibratable element 12 in any desired manner, such head being adapted to receive a suitable treating liquid and to feed the same to the bristles, massaging points, fingers or the like, carried by the head. In the specific form of device illustrated in Figs. 1 and 2, a reservoir 18 for treating liquid is attached to the body portion 10 and to the electromagnet 13 as for example, at points of connection 19 and 19'. The reservoir 18 is provided with an inlet port 20 preferably provided with an air-tight inlet closure 21. Extending upwardly from the bottom of the reservoir 18 is an upwardly extending reentrant tube 22, such tube being preferably curved upwardly, the center of curvature of such reentrant tube 22 being preferably located at or near the center of curvature of the semicircular bend 16 formed in the vibratable element 12. The upper end of the reentrant tube 22 (within the reservoir 18) is provided with a port and a check valve 23 cooperating therewith. The wall of the reentrant tube 22 adjacent the bottom of the receptacle 18 is provided with a port 24.

20 The vibratable element 12 carries a piston 25 curved to slidably fit the reentrant tube 22. This piston may be attached to the vibratable element 12 in any suitable manner, as for example, by means of lock nuts, brazing or the like. An air passageway 26 extends through the piston 25 from its upper end to below the vibratable element 12 where it forms an air intake port 26. The other end of the passageway in the end of the piston 25 is provided with a check valve 27 carried by the end of the piston. The check

valves 21 and 23 are so arranged that when the piston 25 is rapidly reciprocated within the reentrant tube 22 under the influence of the energizing vibratable element 12, air is admitted into the space between the end of the piston 25 and the end of reentrant tube 22 on every down stroke of the piston 25 and such air is forced through check valve 23 into the reservoir 18 on every up stroke of the piston 25, thereby forcing air into the receptacle or reservoir 18 in small but positive increments.

A hollow shampoo head is attached to the lower end of the piston 25 in any suitable manner. In Fig. 2 a shampoo head 30 is illustrated as being made from a suitable resilient material, such as for example, a rubber-like composition, preferably one of the synthetic rubber compounds available on the market under the names "duprene" or "neoprene," these compositions being particularly resistant to oils. The shampoo head illustrated includes a plurality of downwardly extending, pointed fingers 31, certain of the fingers, such as 32, including ducts 33 extending from the ends of the fingers to the chamber within in the head 30, the inner walls of such chamber being indicated at 34.

A conduit 35 extends through the piston 25 and communicates the interior of the shampoo head 30 with a port formed in the side wall of the piston 25 at a point which is slightly above the port 24 when the device is at rest. When the device is at rest therefore, as shown in Fig. 5, the conduit 35 does not communicate with the interior of the reservoir 18. When the device is placed into operation, however, the conduit 35 is repeatedly brought into communication with the port 24 so as to permit liquid from the reservoir to pass into the conduit and into the shampoo head, and, as pointed out hereinbefore, air is pumped into the upper part of the reservoir 18 so as to apply a suitable air pressure to the liquid within the reservoir and facilitate the discharge of liquid from the reservoir into the head, whereupon the liquid will be fed through the ducts 33 and discharged from the ends of the fingers 32 into positive contact with the scalp (or other portion of the body to which the shampoo device is applied).

Attention is called to the fact that in the event the shampoo head 30 is pressed but lightly against the head, a massaging action will take place and liquid from the reservoir 18 will be ejected through the ducts 33 against the scalp. When the shampoo head is firmly pressed against the head a massaging action will take place but the stroke of the piston 25 will be materially shortened and the amount of liquid which is ejected through the head is reduced or eliminated, depending upon the size and location of port 24 with respect to the port leading to conduit 35.

In the modified form of construction shown in Figs. 3 and 4, the body portion 10' of the device again includes an outwardly extending vibratable element 12' which is connected to a shampoo head 40, this head being hollow as shown in Fig. 4 and provided with an inlet port 41 having a removable closure 42, such closure preferably being a minute air hole therein so as to permit some air to enter the head.

The base of the head 40 may be removable and may comprise a flat member 43 carrying downwardly extending fingers such as 44, suction cups 45 or bristles. The fingers 44 may be provided with ducts 46 communicating with the

interior of the head 40. Within the head and rotatable upon the inner surface of the plate member 43 is a disc 47 provided with ports or perforations 48 adapted to be moved into coaxial position with respect to the ducts 46. The valve member 47 may be connected to a shaft 49 extending through a suitable gland 50 carried by the wall of head 40, the upper end of the shaft 49 being bent to form an actuating handle 51. 10 A spring 52 may press the valve member 47 against the base plate 43.

In operating the device of the character shown in Figs. 3 and 4 a suitable liquid is admitted to the hollow head 40 through the port 41, the handle 51 having been first turned so as to place the ports or openings 48 out of registry with the ducts 46. When it is desired to use the device as a simple massage no further adjustments need be made. However, when it is desired to apply a treating liquid during such massaging or shampooing, the handle 51 is adjusted so as to bring the ports or openings 48 into partial or complete registry with the ducts 46, this adjustment regulating the amount of liquid which is supplied to the scalp during the massage or shampoo.

Although specific forms of devices have been described in detail, it is to be understood that the present invention is not limited to the exemplary forms illustrated, since those skilled in the art will appreciate that numerous modifications, changes and adaptations may be made. All changes coming within the scope of the appended claims are embraced thereby.

We claim:

- 35 1. In a vibrating shampoo device, the combination of: a body portion including an electrically operated vibratable element, a reservoir attached to said body, said reservoir being provided with a removable closure and a reentrant tube extending into said reservoir from its bottom, a port in the lower portion of the reentrant tube, said port communicating with the reservoir, a piston carried by the vibratable element and slidably into said tube, a hollow shampoo head carried by the outer end of said piston and a conduit in said piston communicating the hollow shampoo head with the side wall of said piston and adapted to periodically communicate with the port in said reentrant tube.
- 40 2. In a vibrating shampoo device, the combination of: a body portion including an electrically operated vibratable element, a reservoir attached to said body, a reentrant tube extending into said reservoir from its bottom, a port in the lower portion of the reentrant tube communicating with the reservoir, a piston carried by the vibratable element and slidably into said tube, a hollow shampoo head carried by the outer end of said piston, a conduit in said piston communicating the hollow head with the side wall of said piston and adapted to periodically communicate with the port in said reentrant tube, an air duct extending through said piston to its upper end and a check valve carried by the closed inner end of said tube and the inner end of said piston for increasing the pressure in said reservoir when the vibratable element is operated.
- 45 3. In a vibrating massage device, the combination of: a body portion including a reservoir provided with a reentrant tube extending into the reservoir from its bottom; a vibratable element adjacent the bottom of the reservoir; a piston carried by the vibratable element, a por-
- 50 5. In a vibrating shampoo device, the combination of: a body portion including an electrically operated vibratable element, a reservoir attached to said body, a reentrant tube extending into said reservoir from its bottom, a port in the lower portion of the reentrant tube communicating with the reservoir, a piston carried by the vibratable element and slidably into said tube, a hollow shampoo head carried by the outer end of said piston, a conduit in said piston communicating the hollow head with the side wall of said piston and adapted to periodically communicate with the port in said reentrant tube, an air duct extending through said piston to its upper end and a check valve carried by the closed inner end of said tube and the inner end of said piston for increasing the pressure in said reservoir when the vibratable element is operated.
- 55 6. In a vibrating shampoo device, the combination of: a body portion including an electrically operated vibratable element, a reservoir attached to said body, a reentrant tube extending into said reservoir from its bottom, a port in the lower portion of the reentrant tube communicating with the reservoir, a piston carried by the vibratable element and slidably into said tube, a hollow shampoo head carried by the outer end of said piston, a conduit in said piston communicating the hollow head with the side wall of said piston and adapted to periodically communicate with the port in said reentrant tube, an air duct extending through said piston to its upper end and a check valve carried by the closed inner end of said tube and the inner end of said piston for increasing the pressure in said reservoir when the vibratable element is operated.
- 60 7. In a vibrating massage device, the combination of: a body portion including a reservoir provided with a reentrant tube extending into the reservoir from its bottom; a vibratable element adjacent the bottom of the reservoir; a piston carried by the vibratable element, a por-
- 65 8. In a vibrating shampoo device, the combination of: a body portion including an electrically operated vibratable element, a reservoir attached to said body, a reentrant tube extending into said reservoir from its bottom, a port in the lower portion of the reentrant tube communicating with the reservoir, a piston carried by the vibratable element and slidably into said tube, a hollow shampoo head carried by the outer end of said piston, a conduit in said piston communicating the hollow head with the side wall of said piston and adapted to periodically communicate with the port in said reentrant tube, an air duct extending through said piston to its upper end and a check valve carried by the closed inner end of said tube and the inner end of said piston for increasing the pressure in said reservoir when the vibratable element is operated.
- 70 9. In a vibrating massage device, the combination of: a body portion including a reservoir provided with a reentrant tube extending into the reservoir from its bottom; a vibratable element adjacent the bottom of the reservoir; a piston carried by the vibratable element, a por-
- 75 10. In a vibrating shampoo device, the combination of: a body portion including an electrically operated vibratable element, a reservoir attached to said body, a reentrant tube extending into said reservoir from its bottom, a port in the lower portion of the reentrant tube communicating with the reservoir, a piston carried by the vibratable element and slidably into said tube, a hollow shampoo head carried by the outer end of said piston, a conduit in said piston communicating the hollow head with the side wall of said piston and adapted to periodically communicate with the port in said reentrant tube, an air duct extending through said piston to its upper end and a check valve carried by the closed inner end of said tube and the inner end of said piston for increasing the pressure in said reservoir when the vibratable element is operated.

tion of said piston slidably extending into the reentrant tube for rapid reciprocation in said tube, a hollow shampoo head carried by the outer end of the piston; a port in the reentrant tube near the bottom of the reservoir; and a conduit in the piston adapted to periodically communicate the hollow head with the port in the tube when the vibratable element is energized and said piston is reciprocating in the tube, said

piston closing said port when the vibratable element is at rest.

4. In a device of the character described in claim 3, the provision of pump means, actuated by the vibratable element and including said piston, for increasing air pressure in the reservoir when the vibratable element is actuated.

DAN S. BERNS.
